[57] CLAIM

The ornamental design for a device housing, as shown and described.

DESCRIPTION

FIG. 1 is a front and right side perspective view of a device housing illustrating a new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a front and right side perspective view of an alternate embodiment thereof;

FIG. 8 is a left side view of an alternate embodiment thereof; and,

FIG. 9 is a right side view of an alternate embodiment thereof.

The undisclosed views of the second embodiment are identical to those shown in the first embodiment.
